UNITED STATES PATENT OFFICE.

HARLAN E. ECKLER, OF ELYRIA, OHIO.

CUTICLE-CLIPPER.

1,081,896.

Specification of Letters Patent.

Patented Dec. 16, 1913.

Application filed April 8, 1912. Serial No. 689,376.

To all whom it may concern:

Be it known that I, HARLAN E. ECKLER, a citizen of the United States, residing at Elyria, in the county of Lorain and State 5 of Ohio, have invented a new and useful Improvement in Cuticle-Clippers, of which the following is a specification.

This invention relates to a cuticle nipper and the principal object of the invention is 10 to provide a nipper having an improved type of cutting jaw which is so constructed that the cuticle at the top of the finger nail can be easily cut.

Another object of the invention is to so 15 construct the cutting jaw that an elongated finger will be formed which not only forms a portion of the edge, but will also form a device by which the finger nails can be cleaned.

20 Another object of the invention is to provide a cuticle nipper which is simple in construction and which has an improved operating means by which the jaws may be held in a closed position when desired.

25 With these and other objects in view this invention consists of certain novel combinations, constructions and arrangements of parts as will be hereinafter fully described and claimed.

30 In the accompanying drawing: Figure 1 is a top plan view of the clipper. Fig. 2 is a side elevation of the cuticle clipper in a closed position. Fig. 3 is a side elevation of the cuticle clipper in an open position.

35 Fig. 4 is a perspective view of the operating lever.

This invention comprises a strip of resilient material which is doubled intermediate its length to form two jaws 10 and 11, 40 which jaws extend substantially parallel and have their free ends formed into heads of an improved construction. Each of these heads 12 is provided with a side extension forming a tapered finger 13 which finger 45 extends beyond one side of the jaw as clearly shown in Fig. 1. The cutting edge 14 of each jaw is curved from the point 15 to the outer end 16 of the finger 13 thereby forming a cutting edge which conforms to 50 the shape of the cuticle at the inner end of the nail, so that the cuticle can be readily cut. An operating lever 17 has its turned up end 18 pivotally connected with the pivot ears 19 of the jaw 10 and engages the

jaw 11 so that the cutting edges may be 55 brought together from the position shown in Fig. 3 to that shown in Fig. 2. The inner face 20 of the lever 17 is roughened to form a finger nail file and the free end portion 21 is curved slightly and provided 60 with a roughened outer face 22 by means of which the finger will be prevented from slipping from the lever when operating the clipper. A catch 23 is carried by the jaw 11 and engages the free end portion of the 65 lever, as shown in Fig. 2 to hold the lever in the proper position to hold the cutting edges in contacting relation.

When this device is in use, the lever is released from the catch 23 and will assume 70 the position shown in Fig. 3. The cutting edges will then be normally in spaced relation and the cuticle can be very easily cut, after the cuticle has been engaged by the cutting edges the lever is pressed and 75 the edges will be brought together, thus cutting the cuticle from the finger. If it is desired to file the finger nails the lever can be turned to bring the roughened face 20 downwardly and the finger nail can then be 80 easily filed. The finger 13 can be used for cleaning the nails when the cutting edges are in contacting relation, as shown in Fig. 2. When the clip is not in use, the free end of the lever is engaged by the catch 23 and 85 the clip can then be carried in the pocket without danger of the clip catching in the pocket and tearing the lining.

What is claimed, is:

A cuticle nipper comprising a pair of 90 jaws formed from a single strip of resilient material doubled intermediate its length whereby the jaws will extend substantially parallel in spaced relation, a head at the free end of each of said jaws, each of said 95 heads being extended to form a tapered finger extending beyond one side of the jaw and having an arcuate outer edge curving outwardly from one side of the jaw to the end of the elongated finger, pivot ears carried by one of said jaws, and an operating lever pivotally connected with said pivot 100 ears and engaging the remaining jaw for operating said cuticle nipper.

HARLAN E. ECKLER.
